US0D1010112S

(12) **United States Design Patent** (10) **Patent No.:** **US D1,010,112 S**
(45) **Date of Patent:** **** Jan. 2, 2024**

(54) **VIAL ADAPTER WITH VALVE**

(71) Applicant: **KAIRISH INNOTECH Private Ltd.**, Mumbai (IN)

(72) Inventors: **Rishad Kairus Dadachanji**, Mumbai (IN); **Pratul Prakash Potdar**, Daman and Diu (IN); **Keyurkumar Arvindbhai Patel**, Daman and Diu (IN); **Krupal Ashokbhai Chudasma**, Gujarat (IN)

(73) Assignee: **KAIRISH INNOTECH Private Ltd.**, Maharashtra (IN)

(**) Term: **15 Years**

(21) Appl. No.: **29/790,918**

(22) Filed: **Dec. 21, 2021**

(30) **Foreign Application Priority Data**

Jul. 3, 2021 (IN) 345663-001

(51) LOC (14) Cl. **24-02**

(52) U.S. Cl.

USPC **D24/129**

(57) **CLAIM**

The ornamental design for a vial adapter with valve, as shown and described.

DESCRIPTION

FIG. 1 is a top plan view of a vial adapter with valve showing our new design;

FIG. 2 is a bottom plan view thereof;

FIG. 3 is a front side elevational view thereof, wherein the rear side elevational view that is not shown is a mirror image thereof;

FIG. 4 is a left side elevational view thereof, wherein the right side elevational view that is not shown is a mirror image thereof;

FIG. 5 is a top, right, front perspective view thereof;

FIG. 6 is a bottom, rear perspective view thereof; and,

FIG. 7 is a top, left, rear perspective view thereof.

The broken line showing in FIG. 7 is for the purpose of illustrating environment and forms no part of the claimed design.

1 Claim, 7 Drawing Sheets
